UNITED STATES PATENT OFFICE

2,419,330

COMPACTING FLOUR IN BAGS

Helmer Anderson, Minneapolis, Minn., assignor
to General Mills, Inc., a corporation of Dela-
ware

Application May 13, 1943, Serial No. 486,918

17 Claims. (Cl. 259—72)

1

This invention relates to shaping of filled bags and at the same time to compacting or settling flour or other powdered or granular material in bags, particularly paper bags.

Heretofore, the common way of doing this has been to run the filled bags over a jogging table having a conveyor means for feeding the bags forward while they are shaken up and down. Due to the pounding from beneath, the bag often buckles and develops wrinkles in its sides which remain in the filled bag. The bag sometimes leans forward or backward or to one side while the bag is being shaken and this shape too persists in the finished bag. Often the compacting is not well done, leaving the bag soft and easily deformed. All these defects result in a bag which is sloppy in appearance and deficient in the display value it should have.

The bags used may be of any well known type such as "satchel bottom" or "automatic" which are so constructed that they have a rectangular bottom which assumes a naturally rectangular form when filled and shaped. The bags are first filled in a well known manner from a filling tube so that the greater part of the bag above the bottom is nearly round as shown in dotted lines at the left of Figs. 2 and 31. The bags, however, are fed to the machine in such a way as to insure the sides of the rectangular bottom running parallel to the line of travel through the machine. The bag can then be shaped to a nearly rectangular form in which the sides are flat and parallel to the sides of the rectangular bottom.

An object of this invention is to provide a process of and means for shaping of filled bags and at the same time compacting flour and like material in bags which will insure elimination, to a large extent, of some or all of the foregoing defects.

To accomplish this, I suspend the bag by the top and apply a vibrating pressure to the sides to squeeze out the air and compact the flour.

The apparatus for doing this settling is fully described in the following specification and is shown in the accompanying drawings in which

Figure 1 is a side elevation of a machine for compacting flour in bags;

Figs. 2 and 3 are horizontal sections on the lines 2—2 and 3—3 of Fig. 1;

Fig. 4 is an end elevation of the machine viewed from the receiving end;

Fig. 5 is a partial end elevation showing the receiving end of the machine but showing squeezer plates closed;

2

Fig. 6 is a partial vertical section of the machine on the broken line 6—6 of Fig. 1;

Fig. 7 is a vertical section on the broken line 7—7 of Fig. 1 showing the elevator in lowered and raised positions;

Fig. 8 is a partial enlarged section on the line 8—8 of Fig. 1;

Fig. 9 is a section on the line 9—9 of Fig. 8;

Fig. 10 is a developed view of the cams of Fig. 9;

Fig. 11 is a vertical section on the line 11—11 of Fig. 1 showing the vibrator arms in open position;

Fig. 12 is a similar view showing the arms in closed or operative position;

Fig. 13 is an enlarged perspective on the line 13—13 of Fig. 1 showing a one-revolution cam and its operative parts operable by an incoming bag of flour;

Fig. 14 is an enlarged vertical section on the line 14—14 of Fig. 1;

Fig. 15 is a vertical section on the line 15—15 of Fig. 1 showing the vibrator arms of station 5 of the machine, the same being shown in open position;

Fig. 16 is an enlarged vertical section on the line 16—16 of Fig. 1;

Fig. 17 is an enlarged vertical section on the line 17—17 of Fig. 1;

Fig. 18 is an enlarged partial vertical elevation on the line 18—18 of Fig. 1 (and is a fragment of Fig. 21) showing the gears for driving the gripper conveyor;

Fig. 19 is a reduced section on the line 19—19 of Fig. 18;

Fig. 20 is a section on the line 20 of Fig. 18;

Fig. 21 is a slightly enlarged end elevation of the delivery end of the machine;

Fig. 22 is an enlarged horizontal section on the line 22—22 of Fig. 1;

Fig. 23 is a partial view partly in section showing the cam shaft and its associated parts taken on the line 23—23 of Fig. 1;

Fig. 24 is a timing diagram showing the relative positions of various parts associated with the cam shaft;

Fig. 25 is an enlarged partial horizontal section on the line 25—25 of Fig. 1 showing the gripper conveyor carriage;

Fig. 26 is a partial section on the line 26 of Fig. 25;

Fig. 27 is a partial side elevation, partly in section on the broken line 27—27 of Fig. 25;

Fig. 28 is a partial vertical elevation of the bag grippers showing the gripper plates in process of gripping a bag but not locked;

Fig. 29 is the same with the gripper plates locked;

Fig. 30 is a partial enlarged end elevation of the pressure plates of Fig. 4 showing the same equipped with adapters for use with smaller bags;

Fig. 31 is a partial enlarged horizontal section on the line 31-31 of Fig. 1, showing also the adapter plates;

Fig. 32 is a partial elevation similar to Fig. 7 on a reduced scale showing the relative position of the bag grippers for use with 10, 12 and 24½ pound bags; and

Fig. 33 is a diagrammatic perspective showing the principal shafts and their drives.

The embodiment illustrated comprises a main frame consisting of a cast base 40 in which are firmly secured four corner posts or standards 41, 42, 43 and 44 to the top of which is secured a top casting 45. All the mechanism for performing the various steps of compacting the flour is carried upon this frame.

Referring to Figs. 1 and 2, the bag filled with flour at another point (not shown) is received at the lefthand end of the machine and travels to the right in a series of intermediate steps stopping at stations A, B, C, D, E and F where various operations are performed on it. After station F, the finished bag is moved to the right, preferably onto a conveyor (not shown) which carries the bag to a bag closing machine.

In general, the bag having the generally rounded shape shown in dotted lines at the left of Fig. 2 is given an initial pressing on the sides at station A, after which it is moved to station B by means of a short conveyor, raised by an elevator so that the top portion of the bag may be gripped and the bag suspended by one of a series of grippers 50. These grippers are carried by a chain conveyor shown generally as 51 in a carriage 52 and stop at each of the stations B, C, D, E and F in succession. A bracket 54 (Fig. 21) secured to standards 43 and 44 serves to carry much of the apparatus. At station F, the gripper is released, causing the bag to drop onto a platform 53 on the bracket 54, thereby flattening the bottom of the bag. The bag is then moved to the right onto the conveyor (not shown) mentioned above. The carriage 52 is movable up and down on the corner posts 41-44 to accommodate bags of different sizes as will later be described.

For convenience, the driving shafts and gear trains will now be described. Referring to Figs. 1 and 33, a motor 56 drives a belt 57 running over a pulley 57^a on a shaft 58 which has a pinion 59 keyed thereon meshing with a gear 60 keyed on a shaft 61, both these shafts being suitably journaled in bearings carried by the base 40. A bevel pinion 62 keyed on the end of the shaft 61 (Fig. 23) meshes with a bevel gear 63 secured by screws to the back of a continuously driven ratchet wheel 64 journaled on a cam shaft 65 which is intermittently driven as will later be described through a one revolution clutch which is activated by an incoming bag of flour as shown in Figs. 13 and 14. This cam shaft is shown in Figs. 1, 23 and 33 and is suitably journaled in bearings in the base.

The shaft 61 has a sprocket 70 (Fig. 22) driving a sprocket 71 on a shaft 72 by means of a chain 73. This shaft has a pinion 74 meshing with a gear 75 on a shaft 76 which has sprockets 77 and 78 keyed thereon. The former drives a sprocket 79 on a shaft 80 while the latter drives a sprocket

5

81 keyed on a shaft 82, all these shafts being journaled in suitable bearings in the base.

The shaft 58 (Fig. 22) has a bevel pinion 90 meshing with a bevel gear 91 on a shaft 92. The shaft 58 also has a bevel pinion 96 meshing with a bevel gear 97 on a shaft 98. The functions of these shafts will later be described.

The description of the mechanism will in a general way begin at the left side of Fig. 1 and follow the bag through the machine to the right.

Referring to Figs. 1 and 2, a casting 100 is mounted on the standards 41, 42 and a receiving frame 101 is screwed at the top to casting 100 and at the bottom to the base 40. Stations A and B are located on the frame 101 as indicated in Figs. 1 and 2 which show also stations C, D, E and F.

A short belt conveyor 110 located beneath station A (Fig. 33) has a tail shaft 111 and a head shaft 112, the latter being continuously driven by sprockets and a chain 113 from the shaft 82. It serves to propel a filled bag 120A (Fig. 2) which is fed thereon from the left 120 to the next station (B) to the right as soon as the bag 120B in front of it and now located at station B is raised, gripped and moved to station C as will later be described.

Referring particularly to Figs. 2, 4, 30 and 31, a presser frame 125 is bolted to the top of the receiving frame 101 at each side of station A and

30 these are spaced and stiffened at the top by a bolt 126. Bell-crank 127, 128 are pivotally mounted in the frame 125 on pins 129, 130 and are pivotally connected to squeezer plates 131 by pins 35 132. Links 133 connect the bell-crank and the whole provides parallel motion to the squeezer plates which are moved in and out by links 137 40 pivotally connected to cam levers 138 which are pivotally mounted at 139 in the receiving frame 101 and at the inner ends have cam follower rollers 140 rolling on the periphery of the cams 140 keyed on the cam shaft 65.

This shaft makes one revolution for each operation of the bag while the bag is normally at each station. At station A the rounded bag 120, 120A of Fig. 2 is pressed by the squeezer plates into the oblong shape 120B which it still retains when moved to station B. The cams 140 operate to cause the squeezer plates 131 to approach each other to press substantially the entire length of the bag between them for a period of time equal to 110° of arc of the cam shaft (Fig. 24) to give the bag an initial shaping. At the same time this squeezing holds the bag to prevent it from moving forward due to pressure of bags which follow it and to the friction of the short conveyor belt 110.

In normal operation the bag at station B prevents the conveyor 110 at station A from advancing the bag 120A. As the bag 120B advances, as will later be described, the bag 120A likewise advances, the squeezer plates having previously been released.

Referring now to Fig. 7 which is a partial vertical section at station B. An elevator 150 is mounted to slide vertically in suitable guide members 151, 152 bolted to the receiving frame 101. A link 153 is pivotally connected to the elevator 150 by means of a pin 154, the opposite end of the link being connected to a bell-crank 155 which is pivotally connected at 156 (Figs. 1 and 9) to the base 40. The opposite end of the bell-crank carries a cam follower roller 157 operating in the groove 158 in a cam 159, keyed on the cam shaft 65.

The elevator 150 having returned to its normal lower position as shown in full lines in Fig. 7 allows the bag just released from the pressure at station A to be fed forward by means of a feeding conveyor 110. In doing so, the bag passes between vertical guide plates 165 (Figs. 7 and 31) which assist in holding the bag in a vertical position while it is being elevated. On the next rotation of the cam shaft 65 the elevator 150 is lifted from the full line position of Fig. 7 to the dotted line position, at the same time lifting a bag resting thereon from the full line position 120B of Fig. 7 to the dotted line position where the bag can then be grasped by the bag grippers which will now be described.

Bag gripper conveyor

These are shown generally in Figs. 1, 4 and 21 and in detail in Figs. 28 and 29. The grippers 50 are shown in open position in Fig. 4 ready to receive a bag when raised by the elevator. These grippers are carried by the chain conveyors 51, one at each side of the bag, these chains being supported at the bottom of the conveyor by means of parallel tracks 170 on suitable brackets 171 secured to the adjustable carriage 52. The conveyor chains (Fig. 25) run over head sprockets 172 which are mounted on a shaft 173 driven by bevel gears 174, 175, the latter being slidably splined on a vertical shaft 176 which is driven from the cam shaft 65, as will later be described.

The carriage 52 is carried by means of four screw-threaded shafts 180 (Fig. 1) which are threaded through suitable blocks 181 on the sides of the carriage and are journalled in bosses 182 in the sides of the top casting 45. These shafts are provided at their tops with bevel gears 183 which mesh with bevel gears 184 on shafts 185 but which are connected by suitable similar sprockets connected by a chain 186. One of these shafts, as shown in Fig. 4, is provided with a crank 187. By turning this crank, the carriage 52 may be raised and lowered to suit the heights of the different size bags.

Bag grippers

Referring now particularly to Figs. 28 and 29, each bag gripper is mounted on a flight 190 which extends across from one conveyor chain to another and has suitable pins on which are rotatably mounted rollers 191 which roll on the parallel tracks 170.

Plain gripper jaws 195, 196 are carried by levers 197, 198 which in turn are carried on shafts 199, 200 suitably journalled in the flight 190. On similar shafts 201, 202 are mounted other levers on which are carried corrugated gripper jaws 203, 204. The jaw 203 is pivotally mounted at 205 on a bell-crank 206 which in turn is pivotally mounted at 207. The opposite end of the bell-crank is pivotally connected to a short link 208 which passes through a lever 209 and is secured by means of lock nuts 210. This link is normally pressed inwardly by means of a compression spring 211. The pin 207 is carried on the lower end of a lever 212 which is rotatably mounted on the pin 201 and carries a shoulder 213 against which the upper end of the corrugated gripper jaw 203 is slidably and suitably guided. The upper end of the lever 209 is pivotally connected to a link 214 by means of a pin 215. The opposite end of the link 214 is pivotally connected to the upper end of the lever 198 by means of a pin 216.

The levers 197 and 209 are caused to oscillate in opposite directions by means of segmental gears. The upper end of the corrugated gripper

jaw 203 is held against the shoulder 213 by means of a spring 217. The levers 198 and 209 are normally urged to the right by means of a tension spring 218.

The link 214 is hollow and has a locking block 219 mounted therein and adjustably secured by means of bolts 220. This block has a shoulder 221 which is adapted to be engaged by the outer end of a locking finger 222 mounted on a shaft 223 which is suitably journalled in the flight 190 and which carries a release lever 224. The operation of this intermittent feed bag gripper is as follows. With the jaws 195 and 203 separated, as shown in Fig. 4, the bag is raised as shown in dotted lines in Fig. 1 in which position the top of the bag comes between operating pairs of gripping jaws at the two sides of the bag. A latching lever 230, whose construction and operation will later be described, presses the link 214 to the left thereby rocking the levers 197 and 212 toward each other and moving the locking jaws into adjacent position as shown in Fig. 28. A further movement of the link 214 will cause the gripping jaw 203 to slide down with respect to the jaw 195, as shown in Fig. 29, thereby causing an ear 225 to slide down over the inclined upper portion 226 of the jaw 195, thereby firmly locking together the jaws 195 and 203. At the same time the shoulder 221 passes beyond the locking finger 222 which lifts into position behind the shoulder 221 by the action of spring 221A which is attached to the end of a depending arm on the lever 224, thereby locking the parts of the gripper in gripping position. At the same time the lever 198 moves to grip the top of the bag between the grippers 196 and 204 in the same way and by a similar system of levers which have not been described in detail.

The weight of the bag serves to further tighten the hold of the grippers on the bag. This is accomplished by making the jaws slidable with respect to each other and by roughening the inner surface of the outer jaw 203 while the inner surface of the jaw 195 is smooth. Thus, the jaw 203 is pivotally mounted on the bell-crank 206 which swings about the pin 207. Any downward movement of the jaw 203, as shown by the difference in positions of the jaws 195 and 203 in Figs. 29 and 30, results in a toggle action of the bell-crank 206 which brings a much greater pressure between the jaws 195 and 203 even without the application of the additional pressure due to the ear 225 which applies considerable more pressure to the bag, particularly at the top of the gripping jaws. The inside of the jaw 195 is made smooth to prevent damage to the inner liner of multi-wall bags which are often of much thinner material than the outer walls of the bag. The corrugations on the jaw 203 are not sharp enough to cut or tear the outer walls.

The locking and unlocking mechanism for the grippers shown in Fig. 25 will now be described. The latching lever 230 shown in Fig. 28 is also shown at the lefthand side of Fig. 25 and is pivotally mounted at 240 on the carriage 52. The opposite end of the lever 230 is connected through a link 241 with a bell-crank 242 mounted between suitable bearings on the carriage 52 and keyed to a splined shaft 243 (Figs. 1 and 25), the bell-crank moving up and down on the shaft with the carriage as the carriage is adjusted vertically. The shaft 243, as shown in Fig. 1, is journalled in a bracket 244 which is carried

on the casting 100, the shaft having suitable collar for providing vertical movement of the shaft with respect to the bracket 244. At the lower end of the splined shaft 243 is keyed a lever 250 which connects through the link 251 with the bell-crank 252 which is pivotally connected at 253, the opposite end of the bell-crank carrying a cam follower roller 254 which rolls on the face of the cam 255, the latter being keyed on the cam shaft 65.

Thus for each revolution of the shaft 65 the high spot of the cam 255 acting through this system of levers causes the latching lever 230 (Figs. 25 and 28) to move the link 214 to the left (Fig. 28) thereby setting the gripping jaws firmly on the top portions of the bag so that when the elevator 150 descends, which occurs immediately following this gripping action, the gripping jaws retain the filled bag in suspended position. This gripping action is maintained throughout stations C, D and E while the compacting takes place at these stations, the bag being released at station F by a releasing finger which will now be described.

Referring to Figs. 25 and 29 the gripping jaws are released by means of a releasing lever 260 pivotally mounted at 261 on the carriage 52. This lever 260 connects through a link 262 to a lever 263 which is guided between suitable bosses 264 (Fig. 1) on the carriage 52 and which is keyed on a splined shaft 265. Thus the lever 263 moves up and down with the carriage on this splined shaft. This shaft is provided with a bearing carried by the base 40 and has keyed thereon near its lower end a lever 270 which connects through a link 271 with a lever 272 which is pivotally mounted on a pin 273 (Fig. 14), this lever carrying a cam follower roller 275 rolling on a cam 276 on the cam shaft 65, and is pressed by a spring 271a.

As the high spot of the cam 276 operates this system of levers, the lever 260 (Figs. 25 and 29) strikes the release lever 224, thereby knocking the locking finger 222 out of contact with the shoulder 221 (Fig. 28), permitting the spring 218 to cause the bag grippers to return to the full open position shown in Fig. 4, and permitting the bag to drop onto the platform 53 (Fig. 21). The compression of the sides of the bag while suspended, and which has not been described, causes the bottom of the bag to become rounded and dropping it in this way on the platform 53 flattens and squares the bottom of the bag. The rounded shaped bottom makes it difficult to control the bag through the sealing operations.

Flour compacting and bag shaping mechanism

Referring particularly to Figs. 1, 11, 12 and 15, brackets 300, 301 are carried upon the tubular corner standards and to these are secured members 302, 303 (Fig. 11) to which are secured spaced rods 304, 305 in pairs, two on each side of the machine. On the rods 304 are rockingly mounted links 306 and on the rods 305 are similar links 307. These links are parallel and carry at their lower ends spaced parallel pairs of rods 308 and 309 which extend across stations C, D and E and on which are mounted saddles 310 and 311 which swing toward and from the bag by means of this parallel motion. Each saddle carries near its upper end on pins 312, 313 a vibratory pressure plate 316, 317 and this is rapidly oscillated about its point of suspension by means which will later be described. The saddle 310 at station C is con-

nected through a link 320 with a lever 321 which is pivotally connected at 322 on an arm of the casting 100. The lower end of the lever 321 carries a cam follower roller 323 which rolls on cam 324 keyed on the cam shaft 65. A similar lever 321a operated by a similar cam 324a moves the saddle 311 in and out, the levers 321 and 321a being urged inwardly by a spring 318. At the other end of the rods 308 and 309 (station E, Fig. 1) is located a similar pair of levers operated by similar cams (Fig. 23) on the cam shaft 65. It will be noted that all the cams on this shaft are adjustably bolted to collars keyed on this shaft so that they may be individually adjusted.

Thus, the rods 308, 309 and the saddles 310, 311 form a sort of floating carriage for the vibratory pressure plates 316, 317 which are moved in and out in equal amounts on the two sides and at all stations, these plates being drawn back to permit the bags to pass from station to station.

I have provided means such as the extra holes in the link 320 for permitting this floating carriage to swing in further to accommodate narrower widths of bags such as 10 and 12 pound bags (Fig. 32). The bags shown in Figs. 10 and 11 are 24½ pound bags.

The vibrator mechanism will now be described. A connecting rod 340 is connected at the inner end to the pressure plate 316 at each of stations C, D and E while the outer end is operated by a crank (shown in dotted lines in Fig. 12) in a well-known manner on a crank-shaft 345 journalled in bearings on saddles 310. The shaft 345 is driven at a rapid rate by a pulley 346 and one or more V-belts 347 from a pulley 348 on the shaft 92 (Figs. 15 and 22). The vibratory pressure plate 317 is similarly driven from the shaft 98. Belt tighteners 349 on bell-cranks 350 pressed by a spring 351 serve to keep these belts tight.

It will be noted no effort is made to keep the plates 316, 317 vibrating in opposition. This is not necessary since they vibrate so rapidly and the heavy bag has so much inertia it cannot move far in response to pressure from one pressure plate before the opposite pressure plate acts upon it even when these motions are not in opposition.

The effect of moving in the carriages at each side of the bag and of applying this vibratory pressure at a number of stations while the bag is held suspended by the top is to progressively force out air in the flour and to compact it to a marked degree not heretofore attained, thus forming a solid rectangular package which retains its rectangular shape for display and which lends itself to packing in a minimum space in a shipping case.

It will be understood that, if desired, the pressure plates may be pivotally mounted at their bottoms instead of their tops. This might result in somewhat raising the shaft 345.

One-revolution clutch for operating cam shaft

It will be noted that bags enter this machine from the left (Fig. 1) and proceed step by step to the right when the bag leaves the machine. All the mechanism for advancing the bag from station to station and for gripping the top, and for performing various operations on the bag is operated by the cam shaft 65 and this, as will be seen, is controlled by the advent of a bag 120B into station B (Figs. 2 and 13).

As it enters station B, it strikes a trip finger 360 pivotally mounted at 361 and having a lever arm 362 adjustably connected thereto by means of a screw 363 which permits adjustment for dif-

ferent bag sizes. The arm 362 connects through a link 364 with a lever 365 keyed on a shaft 366 suitably journalled in the frame and carrying a lever 367 connected by a link 368 to a lever 369 on a shaft 370 suitably journalled in the frame. A spring 371 urges these parts toward the positions here shown.

The shaft 370 has a lever 380 keyed thereon which connects through a link 381 with one arm of a bell-crank 382 pivotally mounted at 383. A pawl 384 is pivotally mounted at 385 on the other arm of the bell-crank and has a spring 386 holding it against a stop as shown.

This pawl lies in front of the lower end of a detent 390 pivotally mounted on the pin 391 and adjustably positioned by means of an adjusting screw 395 so that its upper end is urged by a spring 396 into the path of the outer end of a finger 400 pivotally mounted at 401 on a lever 402 keyed on the cam shaft 65. The finger 400 carries a pawl 403 which is normally urged toward the ratchet teeth 404 on the inner surface of the ratchet wheel 64 by means of a spring 409.

The operation of this ratchet is as follows: a filled bag 120B traveling to the right as shown by the arrow arrives at station B moving the trip finger 360 thereby causing the pawl 384 to move to the right, moving the detent 390 in a counter-clockwise direction about the pin 391 so that it becomes disengaged from the finger 400. The spring 405 promptly moves the pawl 403 into engagement with the ratchet teeth 404 of the ratchet wheel 64 which is in constant rotation. The pawl 403 rotates with the ratchet wheel for one revolution only, being stopped when the finger 400 again encounters the detent 390 thereby disengaging the pawl from the ratchet wheel and again stopping the rotation of the cam shaft.

Pressure of the finger 400 applied by the spring 414 (Fig. 6) on the detent 390 holds the pawl 403 back against the stop 402a on the lever 402 (Fig. 13) so as to hold the pawl 403 out of engagement with the ratchet teeth thereby preventing wear of the pawl and ratchet teeth as the ratchet wheel rotates.

The purpose of the rather intricate lever arrangement for the clutch control is to provide a safety means in case a bag at station B should fail to be picked up by the bag grippers. The following is an explanation of the function. When bag 120B comes into engagement with trip finger 360, the action through the lever arrangement causes detent 390 to move out of engagement with finger 400 thereby causing pawl 403 to engage with ratchet wheel 64. Through this action it will be noticed that pawl 384 has moved beyond the lower end of detent 390, thereby permitting the detent 390 to return to its normal position. Thus it will be seen that if for any reason the trip finger 360 should remain in open trip position, it would not be possible to trip the machine again until the broken or misshapen bag has been removed from contact with the trip finger 360.

During this one revolution of the cam shaft, the various apparatus operated by the cam shaft is actuated. Thus, the elevator raises, a bag thereon is gripped, all the grippers with their suspended bags are advanced one station, the bag at the first station is compressed, the side rods at stations C, D and E are moved in toward the bags at these stations so as to press them due to the action of the vibrating presser plates, the bag is released at station F, causing it to drop onto the delivery platform thereby flattening the bot-

tom of the bag which has become somewhat rounded due to the action of the vibrator plates, and the bag is ejected from the platform onto a suitable conveyor or table not shown.

Referring to Figs. 16 to 21, the mechanism for operating the conveyor for intermittently carrying the bags from station to station and that for ejecting the bag from the platform 53 at station F will now be described. An interrupted gear 450 is adjustably secured by means of screws 451 to a plate 452 on the cam shaft 65. It will be noted that many of the other cams and gears are similarly mounted for ready individual adjustment on this cam shaft (Fig. 23).

The interrupted gear 450 meshes with an interrupted gear 455 adjustably secured on a shaft 456 suitably journalled in the carriage 52. A bevel gear 460 keyed on this shaft meshes with a bevel gear 461 keyed on a vertical shaft 465 also journalled and carried by the bracket 54. A lever 466 (Fig. 20) keyed on this shaft has a roller 467 adapted to operate in a series of four radial slots 468 of a Geneva gear plate 469 adjustably mounted on a shaft 470 suitably journalled in the carriage 52 and carrying a gear 475 meshing with a gear 476 keyed on the vertical shaft 476 journalled at the bottom in the bracket 54 and near the top (Fig. 21) in an extension of the carriage 52. One revolution of the shaft 465 advances the shaft 470 one-quarter revolution.

The bevel gear 475 is slidably keyed on the splined upper portion of the shaft 476 but journalled in the carriage 52 to permit of vertical adjustment of the carriage and meshes with the bevel gear 474 keyed on the head conveyor shaft 173 as previously described.

Thus, on each revolution of the cam shaft 65, the gear 450 drives the shaft 470 one-quarter revolution, thereby advancing all the grippers a distance equal to the distance between adjacent stations.

Referring to Fig. 18, an interrupted gear 500 keyed near the end of the cam shaft 65 meshes with a gear 501 keyed on a shaft 502 suitably journalled in the bracket 54 and having keyed thereon a bevel gear 503 meshing with a similar gear 504 on a shaft 505 suitably journalled in the bracket. This shaft carries a crank arm 506 adjustably mounted thereon. This crank arm connects through a link 506a with a lever 509 keyed on a short vertical shaft 507 (Fig. 2) suitably journalled in a bracket 508 on the standard 43 and having keyed thereon a lever 509a pivotally connected through a link 510 with an ejector plate 511 slidably mounted on the platform 53.

The bag is guided between plates 520 (Figs. 1 and 2) mounted on brackets 521 which are adjustably mounted on the bracket 301. This insures the bag striking the platform 53 squarely so as to give a square bottom.

This ejector plate operates once for each revolution of the cam shaft to push the compacted and shaped bag which has just been dropped onto the platform off the platform and onto a table 60 or onto another conveyor not shown.

The flour levels are shown in dotted lines in the several bags also shown dotted in Fig. 1. It will be noted that the flour level falls progressively from left to right as the compacting progresses and air is forced out of the flour.

The machine has been described primarily as used for bags of 24½ pound size. The machine, however, is adapted to take smaller bags as 10 and 12 pound bags as shown in Fig. 32, the carriage 52 being raised or lowered accordingly to the proper

height for each size of bag used. At the same time the pins connecting the links 320 with the saddles 310, 311 are set over into the blank inner holes shown in these links to swing these saddles in to adjust for the differences in thickness of the flour bags. Adapter plates 520 (Fig. 30) are secured to the inside of the squeezer plates 131 by means of screws to adapt these to the narrower 10 and 12 lb. bags. These bags have the same horizontal cross section, the only differences being in the height as shown in Fig. 32.

The term "vibratory pressure" as used in the specification and claims is intended to describe a combination of vibration and steady pressure due to the vibratory pressure plates 316, 317 being pivotally mounted at their tops to saddles 310, 311 which are positively moved inwardly while the lower ends of the plates 316 are so rapidly vibrated that the relatively heavy bag of flour does not have time to move under the succession of impacts.

It will be noted the pressure plates do not extend as high as the flour level. The tension of the sides of the flour bag is sufficient that, in connection with the pressure exerted below it, the flour above the pressure plates is also compacted. The levels of the flour are shown in dotted lines in Fig. 1 as falling as the bag advances.

Thus it will be seen I have provided an efficient means for compacting flour in bags and shaping the same and one which avoids the disadvantages incident to the old style shakers which often left the bag misshapen and wrinkled.

While I have shown and described but a few embodiments of my invention, it is to be understood that it is capable of many modifications. Changes, therefore, may be made which do not depart from the spirit and scope of my invention as disclosed in the appended claims.

I claim as my invention:

1. The process of compacting flour in open top bags and shaping same before closing comprising suspending the bag by the open top, and subjecting the sides of the bag to oppositely directed vibratory pressure while so suspended.

2. The process of compacting flour in open top bags and shaping same before closing comprising suspending the bag by gripping opposite sides of the open top, and subjecting the sides of the bag to oppositely directed vibratory pressure while so suspended.

3. The process of compacting flour in open top bags and shaping same before closing comprising suspending the bag by gripping opposite sides of the open top, and subjecting the lower portion of the sides of the bag to vibratory pressure while so suspended.

4. The process of compacting flour in open top bags and shaping same before closing comprising suspending the bag by the open top, subjecting the sides of the bag to vibratory pressure while so suspended, and dropping the compacted bag onto a horizontal surface to flatten the bottom of the bag.

5. Mechanism for compacting flour in bags comprising an intermittently operated conveyor adapted to stop at a plurality of stations, means carried by the conveyor for gripping the top of the open bag, means for elevating a bag to a point where it is caught by the gripping means, and means for applying vibratory pressure to the sides of the bag at a plurality of stations to compact the flour.

6. Mechanism for compacting flour in bags comprising an intermittently operated conveyor,

means carried by the conveyor for gripping the top of the open bag, means for elevating a bag to a point where it is caught by the gripping means, means for applying vibratory pressure to the sides of the bag to compact the flour, a horizontal platform, and means for releasing the bag so that it drops onto the horizontal platform to flatten the bottom of the bag.

7. Mechanism for compacting flour in bags comprising a plurality of stations, a conveyor located in the upper part of the mechanism and having a series of grippers, means for driving the conveyor intermittently so as to cause the grippers to stop at each of the stations in turn, an elevator to lift the bag to the grippers, means for causing the grippers to grip the open bag top to hold the bag suspended, and means for applying vibratory pressure to the sides of the bag to compact the flour.

8. Mechanism for compacting flour in bags comprising a plurality of stations, a conveyor located in the upper part of the mechanism and having a series of grippers, means for driving the conveyor intermittently so as to cause the grippers to stop at each of the stations in turn, means for initially shaping and compacting the bag of flour, an elevator to lift the bag to the grippers, means for causing the grippers to grip the open bag top while elevated, and means for applying vibratory pressure to the sides of the bag while so suspended to compact the flour.

9. Mechanism for compacting flour in bags comprising a plurality of stations, a conveyor located in the upper part of the mechanism and having a series of grippers, means for driving the conveyor intermittently so as to cause the grippers to stop at each of the stations in turn, means for causing the grippers to grip the open bag top while elevated, means for applying vibratory pressure to the sides of the bag while so suspended to compact the flour, a horizontal platform, and means for releasing the bag so that it drops onto the horizontal platform to flatten the bottom of the bag.

10. Mechanism for compacting flour in bags comprising a plurality of stations, a conveyor located in the upper part of the mechanism and having a series of grippers, means for driving the conveyor intermittently so as to cause the grippers to stop at each of the stations in turn, an elevator to lift the bag to the grippers, means for causing the grippers to grip the open bag top while elevated, means for applying vibratory pressure to the sides of the bag while so suspended to compact the flour, a horizontal platform, and means for releasing the bag so that it drops onto the horizontal platform to flatten the bottom of the bag, all said means being driven from a single source.

11. Mechanism for compacting flour in bags comprising a plurality of stations, a conveyor located in the upper part of the mechanism and having a series of grippers, means for driving the conveyor intermittently so as to cause the grippers to stop at each of the stations in turn, an elevator to lift the bag to the grippers, means for causing the grippers to grip the open bag top while elevated, means for applying vibratory pressure to the sides of the bag while so suspended to compact the flour, a horizontal platform, means for releasing the bag so that it drops onto the horizontal platform to flatten the bottom of the bag, and means for raising and lowering the conveyor with respect to the vibratory

pressure means to accommodate bags of different heights.

12. Mechanism for compacting flour in bags comprising a plurality of stations, a conveyor located in the upper part of the mechanism and having a series of grippers, means for driving the conveyor intermittently so as to cause the grippers to stop at each of the stations in turn, an elevator to lift the bag to the grippers at one station, means at a later station for causing the grippers to grip the open bag top while elevated, means for applying vibratory pressure to the sides of the bag while so suspended to compact the flour, a horizontal platform, means for releasing the bag so that it drops onto the horizontal platform to flatten the bottom of the bag, a shaft for operating all said apparatus, the operation of which shaft is controlled by incoming bags, and means for raising and lowering the conveyor with respect to the vibratory pressure means to accommodate bags of different heights.

13. Mechanism for compacting flour in bags comprising a plurality of stations, a conveyor located in the upper part of the mechanism and having a series of grippers, means for driving the conveyor intermittently so as to cause the grippers to stop at each of the stations in turn, an elevator to lift the bag to the grippers, means for causing the grippers to grip the open bag top while elevated, means for applying vibratory pressure to the sides of the bag while so suspended to compact the flour, a horizontal platform, means for releasing the bag so that it drops onto the horizontal platform to flatten the bottom of the bag, a cam shaft for operating all said means, means for driving the cam shaft one revolution at a time, and a trip finger operable by a bag at a given station for causing said driving means to rotate said cam shaft through one revolution whereby failure to grip a bag at said station prevents further operation of the cam shaft until said bag is removed.

14. Mechanism for compacting flour in bags comprising a plurality of stations, a conveyor located in the upper part of the mechanism and having a series of grippers, means for driving the conveyor intermittently so as to cause the grippers to stop at each of the stations in turn, means for causing the grippers to grip the open bag top

to hold the bag suspended, and means for applying vibratory pressure to the sides of the bag while suspended to compact the flour.

15. Mechanism for compacting flour in bags comprising a plurality of stations, a conveyor located in the upper part of the mechanism and having a series of grippers, means for driving the conveyor intermittently so as to cause the grippers to stop at each of the stations in turn, means for causing the grippers to grip the open bag top to hold the bag suspended, and means for applying vibratory pressure to the lower portions of the sides of the bag while suspended to compact the flour.

16. Mechanism for compacting flour in bags comprising means for gripping the top of the open bag to hold the bag and contents suspended, and means for applying vibratory pressure to the sides of the bag to compact the flour, comprising saddles positively movable oppositely toward and from the bag, pressure plates hingedly pivoted at one end to the saddle, and means for vibrating the other end of said plates against the bag.

17. Mechanism for compacting flour in bags comprising means for gripping the top of the open bag to hold the bag and contents suspended, and means for applying vibratory pressure to the sides of the bag to compact the flour, comprising saddles positively movable oppositely toward and from the bag, pressure plates hingedly pivoted at the upper end to the saddle, and means for vibrating the other end of said plates against the bag.

HELMER ANDERSON.
